WIRE STRETCHER

Inman Leslie Patton and Ambrose W. Hughey,
Eldorado, Ill.; Elizabeth E. Hughey, administratrix
of said Ambrose W. Hughey, deceased

Application October 28, 1941, Serial No. 416,826

2 Claims. (Cl. 254—76)

The present invention relates to new and useful improvements in wire stretchers for use particularly by linemen on electric and telephone wires, although it will be understood, of course, that the device may be used for any other purpose for which it may be found adapted and desirable.

An important object of the invention is to provide, in a manner as hereinafter set forth, a stretcher of the aforementioned character which is adapted to be expeditiously engaged with the wire to be stretched at any desired point without the necessity of cutting said wire.

Another very important object of the invention is to provide a stretcher of the character described comprising a novel construction and arrangement whereby the wire may be stretched to the desired tightness without the necessity of re-setting the device.

Still another very important object of the invention is to provide a stretcher of the character set forth comprising a unique construction and arrangement of lever operated jaws for gripping and releasing the wire.

Other objects of the invention are to provide a wire stretcher which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view looking at one side of the device with the grippers in retracted position.

Figure 2 is a view substantially similar to Figure 1, but with the grippers in forward position with a wire engaged therein.

Figure 3 is an elevational view, looking at the opposite side of the device with the grippers in retracted position.

Figure 4 is an elevational view similar to Figure 3, but with the grippers in forward position.

Figure 5 is a fragmentary view in elevation, substantially similar to Figure 4, but with the forward gripper released and in retracted position.

Figure 6 is a top plan view of the device.

Figure 7 is a view in vertical longitudinal section through one end portion of the device, taken substantially on the line 7—7 of Figure 6.

Figure 8 is a vertical longitudinal sectional view through the other end portion of the device, taken substantially on the line 8—8 of Figure 6.

Figure 9 is a cross-sectional view, taken substantially on the line 9—9 of Figure 1.

Figure 10 is a cross-sectional view, taken substantially on the line 10—10 of Figure 5.

Referring now to the drawings in detail, it will be seen that the embodiment of the invention which has been illustrated comprises an elongated base 1 of suitable material. The forward end portion of the base 1 has mounted thereon a hook 2 for connection with an anchor. The sides of the base 1 have formed therein longitudinally spaced grooves or channels 3 and 4.

Mounted on the rear end portion of the base 1 is what may be referred to as a stretching gripper which is designated generally by reference numeral 5. The gripper 5 comprises a carriage 6 which is slidable on the base 1, said carriage including depending flanged side plates 7 which are slidably engaged in the grooves 4. One side portion of the carriage 6 is formed to provide a horizontally extending stationary or fixed jaw 8.

Pivotedly mounted at 9 for swinging movement in a vertical plane on the rear end portion of the carriage 6 is an arm 10. Pivotedly mounted, as at 11, on an intermediate portion of the arm 10 above the stationary jaw 8 and cooperable therewith is a movable jaw 12. Mounted in the forward end portion of the jaw 12 is an inwardly projecting pin 13. The pin 13 is operable in an inclined slot 14 which is provided therefor in the carriage 6 for movably supporting the forward end of the jaw 12. A coil spring 15 is connected to the pivoted arm 10 for yieldingly urging said arm in a direction to close the jaw 12 on the stationary jaw 8.

The base 1 has formed therein, at an intermediate point, a longitudinal slot 16. Pivotedly secured at 17 in the base 1 and operable in the slot 16 is a hand lever 18. Links 19 are pivotally connected, at one end, to the lever 18. Links 20 are pivotally connected, at one end, to the free end portion of the arm 10. The other ends of the links 19 and 20 are pivotally connected by a pin 21 which is operable in an inclined slot 22 which is provided therefor in the forward portion of the carriage 6.

It will thus be seen that the lever 18 is adapted to pull the gripper 5 forwardly on the base 1. The rear end portion of the base 1 has formed therein a longitudinal groove 23 (see Fig. 8). This groove 23 accommodates a spring 24 which is connected to the carriage 6 for retracting said carriage. As best seen in Figure 10 of the drawings, a suitable spring pressed latch or bolt 25 is provided in the base 1 for releasably securing the carriage 6 against sliding movement when it is desired to open the jaw 12 for the insertion of a wire to be stretched, as at 26.

Operable on the forward portion of the base 1 is what may be referred to as a holding gripper

which is designated generally by reference numeral 27. The gripper 27 includes a carriage 28 which is slidable longitudinally on the base 1. The carriage 28 comprises depending flanged side plates 29 which are engaged in the grooves 3 for slidably securing said carriage in position. On one side, the carriage 28 is formed to provide a horizontal stationary jaw 30 which is aligned with the corresponding jaw 8 of the carriage 6. Pivotally mounted at 31 on the rear end portion of the carriage 28 is a forwardly inclined arm 32. A movable jaw 33 has its rear end portion pivotally secured at 34 to an intermediate portion of the arm 32. The movable jaw 33 is positioned above the stationary jaw 30 and is cooperable therewith for clamping the wire 26 therebetween. A laterally projecting pin 35 supports the forward end of the movable jaw 33, said pin being operable in an inclined slot 36 which is provided therefor in the carriage 28.

Links 37 have one end portion pivotally connected to a lug or the like 38 on the forward portion of the base 1. Links 39 have one end portion pivotally connected to the free end portion of the arm 32. The other ends of the links 37 and 39 are pivotally connected by a pin 40 which is operable in a slot 41 provided therefor in the carriage 28.

Fixed on one side of the carriage 28 is an abutment 42. A push bar 43 for the carriage 28 has one end pivotally connected to the connected ends of the links 19 and 20 by the pin 21. The free end of the bar 43 is engageable with the abutment 42 for moving the gripper 27 forwardly in unison with the gripper 5. An elongated opening or slot 44 in the free end portion of the bar 43 accommodates a pin 45 which projects from the arm 32. As the arm 32 swings upwardly the pin 45 engages the upper wall of the opening or slot 44 and disengages the free end of the bar 43 from the abutment 42. As illustrated to advantage in Figure 7 of the drawings, the forward portion of the base 1 has formed longitudinally therein beneath the gripper 27 a slot 46. The slot 46 accommodates a coil spring 47 for retracting the gripper 27 when it is released by the bar 43.

It is thought that the operation of the device will be readily apparent from a consideration of the foregoing. Briefly, the carriages 5 and 27 are moved forwardly through the medium of the hand lever 18 and the former carriage is secured by the latch 25. The movable jaws 6 and 33 are manually opened for the insertion therebeneath of the wire to be stretched, as at 26. Handles or the like 48 are provided on the movable jaws to facilitate this. The latch 25 is then disengaged and the springs 24 and 47 retract the carriages 6 and 28. The lever 18 is now swung rearwardly for pulling the carriage 6 forwardly on the base 1. This, of course, is accomplished through the links 19 and 20 and the arm 10. In this manner the arm 10 is swung forwardly and downwardly for closing the movable jaw 12 on the wire on the stationary jaw 8. At this time the free end of the bar 43 is engaged with the abutment 42. Thus, the carriage 28 is moved forwardly with the carriage 6. As the carriage 28 moves forwardly, the links 37 and 39 push the arm 32 upwardly and rearwardly thereby opening the movable jaw 33. As upward swinging movement of the arm 32 continues, the pin 45

disengages the bar 43 from the abutment 42. When this occurs the carriage 28 is retracted by the coil spring 47 and the links 37 and 39, being pivotally anchored at 38, swing the arm 32 forwardly and downwardly in a manner to close the movable jaw 33 and again clamp the wire on the stationary jaw 30. Thus, the wire is held. The lever 18 is now reversed for moving the carriage 6 rearwardly under the influence of the spring 34. As the carriage 6 moves rearwardly, the movable jaw 12 rides freely on the wire 26. The bar 43 drops behind the abutment 42 and the foregoing operation is repeated.

It is believed that the many advantages of a wire stretcher constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A wire stretcher comprising a base, a stretching gripper slidable on said base, a hand lever pivotally mounted on the base and operatively connected to said stretching gripper, a holding gripper slidable on the base, means releasably connecting said holding gripper to the stretching gripper for actuation in one direction thereby, coacting movable and stationary jaws on the holding gripper for clamping a wire therebetween, means for opening the movable jaw when the holding gripper moves in said one direction on the base and for closing said movable jaw when the holding gripper moves in the opposite direction, means for disconnecting the holding gripper from the stretching gripper, and means for actuating said holding gripper in said opposite direction when it is disconnected from the stretching gripper.

2. A wire stretcher comprising an elongated base, a carriage slidable on said base, a stationary jaw on said carriage, an arm pivotally mounted on the carriage, a movable jaw on the arm cooperable with the stationary jaw for clamping a wire therebetween, a hand lever pivotally mounted on the base, links connecting the arm to said lever for actuation thereby for opening and closing the movable jaw and for actuating the carriage on the base, another carriage slidably on the base, a stationary jaw on the second-named carriage, an arm pivotally mounted on said second-named carriage, a movable jaw on said arm cooperable with the stationary jaw for clamping the wire therebetween, a push bar pivotally connected to the links and engageable with the second-named carriage for moving same in unison with the first-named carriage in one direction, means on the second-named arm for disconnecting the push bar from the second-named carriage, means for actuating the second-named carriage in the opposite direction, and means connected to the base and to the second-named arm for opening the second-named movable jaw when the second-named carriage moves in said one direction on the base and for closing said second-named movable jaw when the second-named carriage moves in the opposite direction on the base.
